UNITED STATES PATENT OFFICE.

RALPH C. SEYMOUR, OF LARCHMONT, NEW YORK, ASSIGNOR TO GOSS PRINTING PRESS COMPANY, OF CHICAGO, ILLINOIS, A CORPORATION OF ILLINOIS.

FOLDING-MACHINE.

1,024,459.

Specification of Letters Patent.

Patented Apr. 23, 1912.

Application filed May 6, 1908. Serial No. 431,252.

To all whom it may concern.

Be it known that I, RALPH C. SEYMOUR, a citizen of the United States, and residing at Larchmont, in the county of Westchester 5 and State of New York, have invented certain new and useful Improvements in Folding-Machines, of which the following is a specification.

The invention relates to folding machines 10 and in certain of its features more especially to machines for folding a printed web or sheets supplied to the folder from a printing press or other suitable source of supply, although in other of its features it is applicable to folders of other kinds.

Objects of the invention are to provide for neat, accurate and very rapid folding; to provide for smooth and uniform handling of the material, without slacking, straining 20 or other abrupt movements thereof, and without rubbing or other injurious contact of the material with the folding devices or otherwise; to provide mechanism therefor simple in construction and simple and reliable in operation; to effect economy of movement in the parts of such a mechanism in proportion to the product secured; to provide such a mechanism which is adapted to receive a web from a rotary or other press 25 and deliver it in folded sheets. These and other objects of invention will in part be obvious and will in part be more fully set forth herein.

The invention consists in the novel parts, 30 combinations, and arrangements and improvements herein shown and described.

The accompanying drawings, referred to herein and forming a part hereof, illustrate one embodiment of the invention, the same 40 serving in connection with the description herein to explain the principles of the invention.

Of the drawings: Figure 1 is a sectional elevation of a machine constructed in part 45 in accordance with the principles of the invention and is taken on the line A—B of Fig. 2. Fig. 2 is a top plan view of the machine shown in Fig. 1. Fig. 3 is a sectional plan view taken substantially on the line 50 C—D of Fig. 1. Figs. 4, 5, 6 and 7 are views, somewhat diagrammatic, illustrating certain parts of the mechanism in different positions. Fig. 8 is a detail in plan and elevation of a fragment of the folding jaw and 55 the spring for pressing same.

Referring to the accompanying drawings, which illustrate by way of example one embodiment of the invention, suitable means for directing the material through the machine are provided. The illustrated form 60 thereof comprises suitable feed and guide rolls 1, guide fingers 2, rolls 3 and fingers or plates 4. The present embodiment is further shown adapted to operate upon a web fed thereinto from a rotary printing 65 press, or other suitable source of supply, and there are shown in operative relation with the web cutting cylinders 5 and 6, suitably mounted upon the machine frame. These cylinders are proportioned to provide 70 a sheet of suitable length and may be timed to sever the sheet from the web substantially at the time that it is engaged by the folding devices.

Suitable folding devices are provided. 75 The invention in certain of its aspects contemplates, in combination with other features as specified by the claims, folding devices including a plurality of sets of traveling folding jaws, and in certain aspects contemplates also that they reciprocate to and from receiving and delivering positions. In certain of its features the invention contemplates further that the sets of jaws reciprocate in fixed relation with respect to each 80 other. The illustrated embodiment, therefore, includes said features and others to be generally set forth hereinafter, together with features which will appear from the detailed description and the appended 85 claims.

In the present embodiment a set of jaws 7 is shown which are yieldably held by suitable means in a closed position. The set of jaws is shown comprising a fixed jaw 8 and 95 a movable jaw 9 acted upon by a suitable spring 91. Said set of jaws is further shown mounted upon a supporting frame or cross-head 10, carried upon ways 11 supported upon the machine frame. Suitable means 100 for giving its travel to the set of jaws are provided and the illustrated form thereof comprises levers 12 pivoted upon the frame of the machine and connected by suitable links 13 to the carriage or cross-head 10. 105 Links 14 are shown connected pivotally to the levers 12 and to cranks 15 carried by a suitable shaft 16 mounted in the frame of the machine and driven in any suitable manner, as for instance by a gear train 17. It 110

- will thus be seen that the set of jaws 7 is reciprocated to and fro between its receiving position and its delivering position as shown in full and dotted lines in Fig. 1.
- 5 Suitable devices for opening the gripper jaws are provided, and for this purpose the swinging jaw 9 of the gripper 7 is shown provided with a tail 18 adapted to contact with a cam 19 to open the gripper when in 10 the delivery position. The tucking blade may fold the sheet into the jaws against their spring, or, if preferred, devices of any suitable or convenient form may be provided for opening the jaws to receive the sheet.
- 15 In certain aspects thereof, the invention contemplates providing traveling folding jaws arranged on either side of the path of the material to be folded. Certain features of the invention contemplate also a plurality of such devices arranged in the same 20 plane. Accordingly there is shown in the accompanying drawings a second set of grippers 20 arranged on the opposite side of the path of the material as it is directed 25 through the machine. Said set as illustrated comprises likewise a fixed jaw 21 and a swinging jaw 22 acted upon by a spring (not shown) similar to spring 91, and mounted upon a suitable carriage or cross-head 23.
- 30 Said carriage or cross-head 23 is arranged to slide upon ways 24 carried upon the machine frame. The swinging jaw 22 is shown as having a trail 25 adapted to co-act with a cam 26 to open the jaw against its spring.
- 35 To cause the sets of jaws 7 and 20 to move in fixed relation, as above indicated, the carriages or cross-heads 10 and 23 are shown connected by pieces 27. The two sets of jaws are thus caused to move together in 40 their travel with the movement of the levers 12 and their associated parts, as likewise appears from Fig. 1 of the drawings.
- Means coöperating with the folding devices to fold or tuck the sheets thereinto are 45 provided. In certain of its aspects, the invention contemplates a single device coöperating with each set of traveling or reciprocating jaws to fold a sheet thereinto. Also, the invention contemplates, in accordance 50 with certain features thereof, providing a device traveling to and fro transversely of the path of the material to coöperate first with one set of folding jaws and then with the other and so as to pass from one 55 side to the other of the material after each successive folding and as the material again feeds along its path. In the illustrated embodiment, accordingly, there is shown mounted intermediately the sets of jaws 7 and 20 a device 28 for coöperating therewith to tuck the sheets thereinto. Said device is shown adapted to reciprocate upon suitable ways 29 and provided with tucking edges 30 and 31. Said tucking edges are further shown oppositely arranged, so
- that the reciprocation of the device or carrier 28 brings each edge successively into operative relation with its set of jaws. For simplicity of construction the edges may be formed on a single blade and are so shown 70 herein. Suitable means for reciprocating said mechanism to and fro are provided and as shown in the drawings it is connected by pivoted links 32 with levers 33 mounted upon the frame of the machine. The form 75 of actuating means shown herein for said levers comprises cams 34 driven by suitable means, as for instance gears 35. The cam 34 will be suitably shaped to give proper movement to the folding or tucking device 28.
- According to one of its features, the invention contemplates providing a folding blade adapted to engage the material and carry it transversely of its path into engagement with the folding devices and at a speed which compensates for the feed of the material so that there is no slacking or straining thereof when engaged by the blade or the jaws. The material is tucked into 90 the jaws as they are moving away from the end point of their travel, the blade at that time moving more rapidly so as to have the requisite relative movement to perform the tucking operation. The speed relation then 95 changes gradually as the movement of the jaws is accelerated and the blade slips out of the jaws leaving the folded sheet therein. It will be understood, therefore, that there are no abrupt movements, no checking, 100 slacking or other abrupt or injurious handling of the material, and no rubbing or scraping of the material over the edge of the blade or other parts of the machine. Exceedingly smooth and harmonious movements of both the material and the machine parts as well as accurate folding of the sheets are thus secured even when running 105 at high speeds. Means for effecting the foregoing are provided, and as a part of the embodied form thereof the actuating parts for the member 28, the material feeding devices, the folding jaws and associated parts are constructed, arranged and timed to effect the functions and results above set 110 forth.
- Suitable receiving devices for receiving the folded sheets from the grippers may be provided and as shown herein said means comprise traveling pockets 36 mounted upon 115 the machine frame and working over suitable rolls 37 which may be driven in any desired manner. In the present embodiment two separate series of such pockets are shown, arranged on either side of the machine, in operative relation with the respective folding devices.
- The manner of operation of the herein-described mechanism is substantially as follows: The machine will be described as op-

erating upon a web, although in many of its features it is equally capable of folding sheets. A web 38 is led through the machine and is fed downwardly along its path by the directing devices. The folding or tucking device 28 will then be at one side of the web 38, substantially as shown in Figs. 1 and 4 of the drawings. About the time that a page length or other fold length 10 has passed the tucking edge, the tucking device 28 moving transversely to the path of travel of the sheet or web 38 engages it substantially as shown in Fig. 5 and moves it toward and into the set of folding jaws upon 15 the opposite side of the web, the blade acting to tuck the sheet into the jaws against the pressure of the closing spring, as shown in Fig. 6. The functions and relations of the parts during the folding operation have 20 already been set forth. The cutting cylinders 5 and 6 are properly timed to sever the sheet from the web substantially at the same time that it is engaged by the folding jaws, as will appear from Fig. 7 of the drawings. 25 The folding jaws, actuated by their driving connections, move backwardly and as they reach the delivery position the cam 19 or 26, as the case may be, acts to open its gripper, as will be understood by reference to Fig. 30 1, to deliver the sheet. It will be understood that as one set of folding jaws recedes from its receiving position to its delivery position the other set advances from the delivery to the receiving position. The tucking device is now at the opposite end of its travel and as the end of the web feeds downward along its path of travel it now passes along the other side of the tucking device and between it and the other set of folding 35 jaws. The tucking device 28 now begins its movement, the opposite tucking edge engaging the material to act upon it again, this and the succeeding operations occurring substantially in the manner hereinabove described.

It will be understood from all the foregoing that a machine has been provided constructed in part in accordance with the principles of the invention and illustrating 50 said principles, and that said machine realizes the objects of invention and the advantages herein set forth, together with other objects and advantages.

The invention, in its broader aspects, is 55 not limited to the particular constructions shown, nor to any particular constructions by which it has been or may be carried into effect, as many changes may be made in the construction without departing from the 60 main principles of the invention and without sacrificing its chief advantages.

What I do claim as my invention and desire to secure by Letters Patent, is:

1. A folding machine including in combination, a plurality of sets of traveling

folding jaws, a reciprocating, non-rotating device coöperating with a plurality of said sets of jaws to fold a sheet thereinto, and means for opening a set of jaws to release its sheet at a delivery point in the travel of the 70 jaws.

2. A folding machine including in combination, a plurality of sets of reciprocating folding jaws, means for presenting the material at the place of folding, and a reciprocating device coöperating with each set of jaws to fold a sheet thereinto. 75

3. A folding machine including in combination a plurality of sets of traveling folding jaws, a folding device reciprocating in a straight path to fold the material into different sets of jaws in succession, and means for receiving the folded sheets from the jaws. 80

4. A folding machine including in combination a plurality of sets of traveling folding jaws, means acting to hold each set of jaws yieldably in the closed position, a device coöperating with each set of jaws to tuck a sheet thereinto against said yieldable holding means to fold same and means for opening the jaws to release the sheet. 85

5. A folding machine including in combination a plurality of sets of traveling folding jaws, reciprocating means coöperating with a plurality of said sets of jaws to fold a sheet thereinto, and means moving independently of the aforesaid means to bring the material to the place of folding. 90

6. A folding machine including in combination a plurality of sets of traveling folding jaws for engaging the material to be folded at the fold line only, movable means coöperating with each set of jaws to fold a sheet thereinto, means unconnected with 100 aforesaid means for conveying and directing the material to the place of folding. 105

7. A folding machine including in combination, a plurality of sets of traveling folding jaws, a non-rotating device movable into 110 operative relation with a plurality of said sets of jaws to fold a sheet thereinto, and means for opening a set of jaws to release its sheet at a delivery point in the travel of the jaws. 115

8. A folding machine including in combination, a plurality of sets of traveling folding jaws, a non-rotating device movable into operative relation with a plurality of said sets of jaws successively to fold a sheet 120 thereinto, and means for opening a set of jaws to release its sheet at a delivery point in the travel of the jaws.

9. A folding machine including in combination a plurality of sets of reciprocating 125 folding jaws and a device engaging the material to tuck it into various sets of jaws successively, said device being disengaged from the material during the feed thereof.

10. A folding machine including in com- 130

- 2
- 5 combination, a plurality of sets of reciprocating folding jaws, means for presenting the material at the place of folding and a reciprocating device coöperating with each set of jaws successively to fold a sheet thereinto.
- 10 11. A folding machine including in combination, two sets of folding jaws reciprocating in the same plane, means for supplying material to the place of folding, and means located between said sets of jaws and coöperating with each set to fold a sheet thereinto.
- 15 12. A folding machine including in combination, two sets of folding jaws reciprocating in the same plane, means for supplying material to the place of folding, and a tucking device located between said jaws and reciprocating in the same plane therewith to fold a sheet into one set of jaws and then a sheet into the other.
- 20 13. A folding machine including in combination, a plurality of sets of folding devices, each set moving between its own receiving and delivering positions, means for directing the material to be folded contiguous to the receiving positions and means for tucking the material into each set of folding devices successively when in receiving position and means at each of said delivering positions for receiving the folded sheet.
- 25 14. A folding machine including in combination, a plurality of sets of folding jaws, each set moving between its own receiving and delivering positions, means for directing the material to be folded contiguous to the receiving positions and means for tucking the material into each set of folding jaws successively when in receiving position and means at each of said delivering positions for receiving the folded sheets.
- 30 15. A folding machine including in combination, a plurality of sets of folding jaws reciprocating in fixed relation between a receiving position and a delivering position, and means for tucking a sheet into each set of jaws when in receiving position and means at each of said delivering positions for receiving the folded sheets.
- 35 16. A folding machine including in combination, two sets of folding jaws reciprocating in fixed relation between a receiving position and a delivering position, and means located between said sets of jaws for tucking a sheet into each set when in the receiving position and means at each of said delivering positions for receiving the folded sheets.
- 40 17. A folding machine including in combination, two sets of folding jaws reciprocating in fixed relation between a receiving position and a delivering position, and means located between said sets of jaws and reciprocable to tuck a sheet into one set of jaws and then into the other when in the receiving position and means at each of said
- 45 delivering positions for receiving the folded sheets.
- 50 18. A folding machine including in combination, a plurality of sets of folding jaws traveling in fixed relation, a device for tucking a sheet into each set of jaws successively, and a device for each set of jaws for receiving the folded sheets therefrom.
- 55 19. A folding machine including in combination, a plurality of sets of traveling folding jaws, means for presenting the material at the place of folding, a device provided with a plurality of tucking edges, and means for reciprocating said device to cause one tucking edge to tuck a sheet into one set of jaws and another tucking edge to tuck a sheet into another set of jaws.
- 60 20. A folding machine including in combination, two sets of reciprocating folding jaws, means for presenting the material at the place of folding, a device located between said sets of jaws and having oppositely arranged folding edges, one edge coöperating with one set of jaws and the other edge with the other set of jaws to fold a sheet thereinto.
- 65 21. A folding machine including in combination, two sets of reciprocating folding jaws, means for feeding a material to be folded between said sets of jaws, and a device, having two oppositely arranged tucking edges, and reciprocating transversely of the path of the material to tuck it with one of said tucking edges into one set of jaws and then with the other edge into the other set of jaws.
- 70 22. A folding machine including in combination, two sets of reciprocating folding jaws, means for feeding a material to be folded between said sets of jaws, and a device traveling transversely of the path of the material to tuck it into each set of jaws successively.
- 75 23. A folding machine including in combination, two sets of traveling folding devices, means for directing a material to be folded along a path between said sets of devices, and a device traveling transversely to said path to fold the material into each of said devices successively.
- 80 24. A folding machine including in combination means for feeding the material to be folded, a folding device located beside the path of the material to be folded, and means for engaging and moving the material out of its path and into operative relation with said folding device, and actuating means for said engaging and moving means by which the speed of said moving means compensates for the feeding movement of the material so as to keep it stationary with respect to said means at the place of engagement.
- 85 25. A folding machine including in combination means for feeding the material to be folded, folding jaws located beside the
- 90
- 95
- 100
- 105
- 110
- 115

- 125
- 130

- path of travel of the material to be folded, a folding blade moving transversely of the path of the moving material to engage it and tuck it into said jaws, and actuating 5 means for said blade by which the speed of the blade compensates for the feed of the material so that there is no slipping of the material over the blade during said transverse movement.
- 10 26. A folding machine including in combination, two sets of traveling folding jaws spaced apart, means for directing a web of material between said sets of jaws, means for severing the material into sheets, and means 15 movable transversely to the path of the material to engage it on one side to move it from its path and tuck it into one set of jaws and so as to be positioned on the opposite side of the material as it again feeds 20 along its path.
27. A folding machine including in combination, two sets of traveling folding jaws spaced apart, means for directing the material to be folded between said sets of jaws, 25 and means movable transversely to the path of the material to engage it on one side to move it from its path and tuck it into one set of jaws and so as to be positioned on the opposite side of the material as it again feeds 30 along its path.
28. A folding machine including in combination, means for directing the material to be folded through the machine, a plurality of sets of folding jaws traveling to and 35 from the material on opposite sides thereof, means for presenting the material at the place of folding and means for tucking the material into one set of jaws and then into another.
- 40 29. A folding machine including in combination, means for directing the material to be folded through the machine, a plurality of sets of folding jaws movable to and from the material on opposite sides thereof, means 45 for tucking the material into one set of jaws and then into another, and means for serving the material intermediately the folded points.
30. A folding machine including in combination, means for directing a web through the machine, a plurality of sets of folding jaws traveling to and from the web on opposite sides thereof, a tucking device reciprocable across the path of the web to tuck it 55 into one set of jaws and then into another, and cutters for severing the web.
31. A folding machine including in combination, means for directing a web of material through the machine, two sets of folding jaws arranged in the same plane on either side of the web and reciprocable to and from the web, a reciprocating tucking device traveling across the path of the material to tuck it into one set of jaws and then 60 into the other set, and cutting devices for severing the folded parts from the web.
32. A folding machine including the combination, means for directing a web of material downwardly through the machine, rotary cutters, two sets of folding jaws arranged in the same plane on either side of the web and reciprocable to and from the web, a reciprocating tucking device traveling across the path of the material to tuck it into one set of jaws and then into the other set, and receiving means arranged at either side of the machine to receive the folded sheets from the respective folding jaws.
33. A folding machine including in combination, means for feeding material to be folded, a reciprocating tucking blade moving transversely to the path of travel of the material at a speed which compensates for the feed of the material, folding jaws for receiving the material from said blade while moving in the same direction, and means for moving said parts.
34. A folding machine including in combination, means for feeding material to be folded, folding jaws reciprocable toward and a way from said material and a folding blade for tucking the material into said jaws while they are so moving away.
35. A folding machine including in combination, means for directing a web of material through the machine, two sets of folding jaws reciprocable in the same plane and in fixed relation with respect to each other, said sets of jaws being arranged on either side of the path of the web, a folding device having two edges reciprocating across the path of the web at a speed to compensate for the feed of the web to engage and tuck it into each set of folding jaws in succession, web severing devices, and sheet receiving means for each set of jaws.
36. A folding machine including in combination a plurality of sets of reciprocating folding jaws, means for tucking a web of material into a plurality of the sets of jaws successively, and means for severing the material between the supply and said tucking means and between each successive fold.
37. A folding machine including in combination a plurality of sets of traveling folding jaws engaging the material only at the line of fold, a movable device co-operating with each set of jaws to fold the material thereinto, means for directing the material to the place of folding, and means for cutting the material, said directing and cutting means acting on the material before it reaches the place of folding.
38. A folding machine including in combination means for feeding the material to be folded along a path, a set of traveling folding jaws at one side of said path, another

6
set of traveling folding jaws on the other side of said path, said sets of folding jaws being presented alternately, contiguously to the path of travel of the material, a folding blade passing to and fro across the path of the material to be folded to fold said material first into one set of folding jaws and then into another.

39. A folding machine including in combination means for feeding from a web the material to be folded along a path, means for severing the material into sheet lengths, a set of traveling folding jaws at one side of said path, another set of traveling folding jaws on the other side of said path, said sets of folding jaws being presented alternately, contiguously to the path of travel of the material, a folding blade passing to and fro across the path of the material to be folded to fold said material first into one set of folding jaws and then into another.

40. A folding machine including in combination means for feeding from a web the material to be folded along a path, means for severing the material into sheet lengths, a set of folding jaws reciprocating toward and from the material to be folded, another set of folding jaws reciprocating toward and from the material to be folded on the other side of said path, said sets of folding jaws being presented alternately contiguously to the path of travel of the material, a folding blade passing to and fro across the path of the material to be folded to fold said material first into one set of folding jaws and then into another.

41. A folding machine including in combination means for feeding a web of material to be folded along a path, a set of folding devices on one side of said path of travel of the material, a set of folding devices on the other side of said path of travel of the material, a folding blade traveling to and fro intermittently across said path of travel to tuck the material into one of said folding devices and remaining at rest for a

period to permit the material to be fed along its path of travel past said blade, preparatory to being tucked into the other folding device upon the next movement of the 50 blade, and means for severing the sheet from the web just after it has been folded into a folding device.

42. A folding machine including in combination means for feeding the material to 55 be folded along a predetermined path in sheet lengths, a folding device at one side of said path reciprocating between a point contiguous to said path and a place of delivery, a folding device at the other side of said path of travel reciprocating between a point contiguous to said path of travel and a place of delivery, and a folding blade reciprocating across said path of travel of the material to fold a sheet into one of said folding devices and remaining upon that side of the path of travel until another sheet has been fed past said blade.

43. A folding machine including in combination means for feeding a web substantially vertically downward along a path of travel, means for severing the web into sheet lengths, a folding device at one side of said path reciprocating between a point contiguous to said path and a place of delivery, a folding device at the other side of said path of travel reciprocating between a point contiguous to said path of travel and a place of delivery, and a folding blade reciprocating across said path of travel of the material to fold a sheet into one of said folding devices and remaining upon that side of the path of travel until another sheet has been fed past said blade.

In testimony whereof, I have signed my 85 name to this specification, in the presence of two subscribing witnesses.

RALPH C. SEYMOUR.
